UNITED STATES PATENT OFFICE.

ERNEST A. BICKFORD, OF WORCESTER, MASSACHUSETTS.

SLIPPER.

Application filed March 26, 1923. Serial No. 627,549.

To all whom it may concern:

Be it known that I, ERNEST A. BICKFORD, a citizen of the United States, residing at Worcester, in the county of Worcester and 5 State of Massachusetts, have invented a new and useful Slipper, of which the following is a specification.

This invention relates to a slipper of the turned variety, and the principal object 10 thereof is to provide such slipper with elastic means for securing the upper to a permanent soft, comfortable lining for the inner sole in order to prevent the stitches at that point tearing out when the slipper 15 is worn.

Reference is to be had to the accompanying drawings, in which—

Fig. 1 is a longitudinal sectional view 20 of a complete slipper constructed in accordance with this invention;

Fig. 2 is a similar view showing it in the process of manufacture before it is turned; and

Fig. 3 is a fragmentary plan.

Referring first to Fig. 2 it will be seen 25 that the slipper is made with the upper 10, preferably of felt, sewed to the outer sole 11 and a lining 12 along the edge of the sole by a row of stitches 13 passing into 30 a tape 14 of knitted or braided material itself sewed to the edge of the insole 16. The raw edges project outwardly in the position shown in Fig. 2 but when turned 35 they are brought inside and concealed. Over this lining, but under it in the position in which the slipper is worn, is a loose heavy packing 15 of felt or similar material.

This is not sewed to the other parts.

Beyond this is the insole 16 which 40 consists of a piece of lamb's skin with the wool upon it on its inner surface. This is what is ordinarily known as lamb's wool. This skin itself constitutes the insole and to it is sewed the tape 14 by a line of stitches 17. 45 Thus, the above mentioned raw edges are concealed by the lamb's wool, the edges of which cover them up. The tape elastically binds the raw edge of the upper and the lamb's wool face or skin so as to avoid the 50 projection of a projecting ridge that will irritate the feet, and also securely encloses everything inside, so that it constitutes a finishing line around the sole. Projecting up from the skin is the wool itself which 55 is part thereof and is not artificially attached.

At the heel, to allow for the extra thickness of the felt packing, the tape is sewn to two pieces of felt and the lower one 20 is sewed to the outsole. 60

After the slipper is completed in this way as shown in Fig. 2 it is turned to the position shown in Fig. 1, which is the condition in which the slipper is worn. By the use of the tape sewed directly on the 65 lamb's wool insole and stitched to the outsole and upper, the elasticity of the tape permits it to yield to the foot. Thus there is no likelihood of the stitches tearing out of the insole. The construction also is much 70 easier. By sewing the braided tape to the edge of the leather first and then sewing together with an overstitch the lower edge of the upper and the outside edge of the tape, the slipper is finished with an economy of 75 time and labor.

I am aware of the fact that lamb's wool has been used on separate soles made and sold as soles and intended to be provided with an upper crocheted upon them. My 80 invention is entirely different, however, as I produce a manufactured turned slipper with a lamb's wool inner sole and thus get the advantage of the hand-made slippers which have been used before, but at the 85 same time I also get the advantage of manufacture by machinery and am enabled to produce the articles in quantities.

Although I have illustrated and described only a single form of the invention I am 90 aware of the fact that modifications can be made therein by any person skilled in the art without departing from the scope of the invention as expressed in the claims.

Therefore I do not wish to be limited to 95 all the details of construction herein shown and described, but what I do claim is:—

1. As an article of manufacture, a felt turned slipper having sewed directly in contact with the outer surface of the upper 100 thereof, a lamb's wool inner sole, and having a piece of yielding material surrounding the sole and connecting it with the upper and lying over the right inturned edge 105 of the upper.

2. As an article of manufacture, a turned slipper having an inner sole consisting of a lamb's skin with the wool thereon, the flesh side being applied over the sole of the slipper and having a yielding tape sewed 110 around it, said tape being secured to the upper along the inner surface thereof at the

bottom throughout the periphery of the sole, and a felt padding underneath said lamb's skin throughout its area.

3. As an article of manufacture, a turned slipper having an upper and an outsole sewed together around the latter with the raw edges extending inwardly, a tape cov-

ering both of said raw edges, and an insole consisting of lamb's wool having its edges sewed to the tape inside the slipper. 10

In testimony whereof I have hereunto affixed my signature.

ERNEST A. BICKFORD.
